CONCENTRATOR

Filed June 6, 1921

2 Sheets-Sheet 2

UNITED STATES PATENT OFFICE.

FRANK E. HAWKESWORTH, OF TONAPAH, NEVADA.

CONCENTRATOR.

Application filed June 6, 1921. Serial No. 475,396.

To all whom it may concern:

Be it known that I, FRANK E. HAWKESWORTH, a citizen of the United States, residing at Tonopah, in the county of Nye 5 and State of Nevada, have invented a new and useful Concentrator, of which the following is a specification.

My invention relates to the art of saving values from mineral bearing substances, being more particularly a dry concentrator. 10 In some forms of concentrators now in use it is customary to use a fixed riffle on the surface of the concentrator in which case the concentrator so constructed must be stopped at intervals in its operation for the purpose of removing the values from the riffles, consequently considerable time is lost. 15 One of the principal objects of my invention is to produce a table having riffles 20 thereon of simple form and construction which continuously during the operation deliver the values caught by the riffles to a conveyor or receptacle used for that purpose.

Another object of my invention is to produce a concentrator of the class described of simple form and construction in which the agitation of the table surface is produced by the alternate application of pressure and vacuum to the same. Other 30 objects and advantages will appear herein-after from the following description.

Referring to the drawings which are for illustrative purposes only:

Fig. 1 is a side elevation partly in section of a concentrator embodying my invention.

Fig. 2 is an enlarged sectional view of a portion of the table shown in Fig. 1.

Fig. 3 is a vertical sectional view looking from the rear of the machine shown in Fig. 40 1, such sectional view being taken through the air and vacuum valves.

Fig. 4 is an enlarged sectional view on line 4-4 of Fig. 2, a portion of the same 45 being broken away to better illustrate the construction.

Fig. 5 is an enlarged sectional view of the screen construction.

The apparatus consists of a supporting 50 frame having uprights 11, 12 and 13 and timbers 14. Supported between the uprights 11 and 12 is the table generally indicated at 15, which table consists of side members 16 and 17, the side member 16 being deeper than the side member 17 and the

two members being connected at the bottom to an inclined floor 18.

20 designates an apron which delivers the material to be worked from a hopper 21 to the surface of the concentrator table, this 60 surface consisting of a series of screens 22 having interposed therebetween riffles 23. The material passing over the last riffle 23 is discharged over a plate 24 which forms a continuation of the table. Each riffle 23 65 consists of a narrow casing which extends transversely across the table, made of sheet metal and consisting of an inlet portion 25 and an outlet portion 26, the inlet portion 25 discharging into a feed chamber 27 and 70 the feed chamber 27 discharging into the outlet portion 26 which is at the opposite side of the feed chamber to the inlet portion. The casing of which the riffle is formed is preferably made of two plates 30 75 and 31 braced or held apart at intervals by means of spacers 32, the plate 30 being formed with a curved portion or pocket 33 which, together with the off set portions 34 of the plate 31, form the feed chamber 27. 80 The plates 30 and 31 are secured in any suitable manner to end plates 35 preferably formed of cast metal in which are supported bearings 36 of a shaft or spindle 37. The shaft 37 extends longitudinally through 85 the chamber 27 and is provided with wings or paddles 38 secured thereto in any suitable manner.

The lowermost riffle 23 is placed against the end wall 40 of the table, and the other 90 riffles are placed against cross-bars 41, the riffles being supported in the table by the hub 42 of the bearings 36 which extend through the side walls 16 and 17 of the table. The shafts 37 extend through the side 95 walls of the table at one side thereof and are each provided with a worm wheel 44 engaged by worms 45 on a shaft 46, the shaft 46 being driven from a worm 47 on a shaft 48 through the medium of a worm 100 wheel 49 secured to the shaft 46.

The shaft 48 is driven through gears 50 and 51 from a shaft 52 which in turn is driven from a shaft 53 by a worm 54 thereon engaging with a worm wheel 55 on the 105 shaft 52. The shaft 53 is provided with a pulley 56 driven by a belt 57 from a pulley 58 on a shaft 59, the shaft 59 being mounted in suitable bearings 60 supported on the frame of the apparatus and driven by means 110

of a pulley 61 from any suitable source of power.

Arranged between each riffle 23 are the screens 22 consisting of a frame 65 over which is secured the screen body 66. This consists of a sheet of fine wire mesh 67 of about one-eighth (1/8) of an inch drawn over the frame as tight as possible and tacked fast to the under side of the frame. Over this is placed one thickness of burlap 68 likewise drawn tight and tacked fast, and over the burlap is placed, in the same manner, two or three thicknesses of medium weight muslin indicated at 69 and over this a sheet of very light wire mesh indicated at 70, which is primarily for the purpose of protecting the surface of the muslin from wear of the material passing thereover. The wire screen 67 is primarily for the purpose of giving the screen the necessary strength and the burlap and muslin are for providing a sufficient resistance to the passage of air therethrough as hereinafter referred to and for the purpose of carrying the material being concentrated over the table.

After the layers of the different materials are placed over the frame, as hereinabove referred to, the layers may be stitched together as indicated at 71. The screens when so made up are placed in the table, one side or edge of the screen frame resting on the body of a riffle as shown in Fig. 2, the opposite side resting on the cross-bars 41 and the two ends upon cleats 72 secured to the inner side of the table. The screens 22 are firmly held in such position by means of strips 74 which extend along the table above the screens, being secured to the sides 16 and 17 of the table by wood screws indicated at 75. The screens are further held firmly in place by means of rods 76 which engage eyes 77 secured to cross pieces 78 on the screen frames, the rod 76 extending through the floor 18 of the table and nuts 79 being provided to secure the rods in the floor of the table.

It is to be noted that the cross pieces 78 in the screen frames are considerably below the screen surface and the sides of the frame are beveled as indicated at 80 so that the same present a very small edge to the screen surface thereby allowing the full extent of the exposed screen surface to be agitated in the manner hereinafter described.

Leading into the table, under the screens 22 therein, is an air passage 82 which connects with pipes 83 and 84, the communication between the pipe 83 and the air passage 82 being controlled by the valve 85 and the communication between the pipe 84 and the air passage 82 being controlled by a valve 86. The valve members 87 and 88 in the valves 85 and 86 respectively are connected by means of rods 89 and 90 respectively to

eccentrics 91 and 92 respectively on the shaft 59, such eccentrics being timed so that when one valve member is in raised or open position the other valve member is in lowered or closed position.

The pipe 83 is connected to a suitable source of constant supply of air under pressure, such as supplied by an ordinary low pressure blower of the rotary type (not shown). The pipe 84 is connected to any suitable apparatus (not shown) for producing a partial vacuum in the pipe 84.

The apparatus is operated in the following manner:

The material to be worked is fed from the hopper 21 to the apron 20, then to the table surface comprising the screens 22, which surface is practically continuous except for the riffles which extend across the table between the screens. The plate 30 of each riffle 85 extends above the surface of the table as indicated at 95, whereas the upper edge of the plate 31 is substantially level with the screen surface.

The angle of inclination of the table is approximately twenty-one (21) degrees, which is not sufficient to cause the material to slide down and over the table. The passage of material over the table is caused by repeated alternate impulses of air pressure and the application of vacuum to the screens. When working what is commonly known as placer material, these impulses are made to occur at the approximate rate of about one hundred and fifty per minute and the pressure placed upon the screen is just sufficient to cause the screen to bulge slightly upwardly. This impulse is caused by the admission of air under pressure from the pipe 83 to the passage 82, thence into the table under the screens, and immediately following each impulse the valve member 87 cuts off such air pressure, the valve member 88 opens and the vacuum in the pipe 84 acting through the passage 82 and in the bottom of the table below the screens, causes the screen surfaces to recede below their normal tension line leaving the material on the table momentarily in suspense.

During the first or upward impulse, the air pressure causes a portion of the air to pass through the screens and through the material passing thereover. This causes the lighter material in the mass to fly upward and allows the heavier particles to be gravitated downward. The downward impulse caused by the vacuum draws the screen body down slightly faster than the whole would come by gravitation and the tension on the screen body and at the same time drawing the screen body below the tension line thereby giving the screen body or surface more action. The limit of this action or movement of the screen body up and down and the rapidity of the impulses is regulated so

as not to bounce or jostle the material being concentrated, this regulation being made by regulating the speed and opening of the valves 85 and 86 as well as the air pressure 5 and the vacuum. The repeated impulses above referred to cause the material to flow down and over the table in a constant and even stream, the heavier particles seeking the bottom and sliding along the screen surface to the riffles where they are stopped by the edge 95 of the riffles and collected over the open top of the riffles through which they gravitate to the feed chamber 27 where the flow or passage of the concentrates 10 through the riffles is more or less retarded, being regulated by the operation of the shaft 37, the blades thereon removing the concentrates from the feed chamber to the portion 15 26 or discharge part of the riffles from which they are discharged.

In the form of table shown in Fig. 1, 100 designates a trough which is provided with a partition 101, the first two riffles of the table discharging in front of the partition 25 into the trough 100 from which they are discharged through an outlet opening 102 into any suitable receptacle, the balance of the riffles discharging into the lower portion 30 of the trough from whence they are also delivered to any suitable receptacle.

It is understood that the concentrates caught by the first two riffles on the table are of richer value than those caught in the succeeding riffles on the table and for this 35 reason the concentrates from the first two riffles are preferably separated from the balance of the concentrates. The lighter

material on the table passes downwardly over the riffles and the tailings are discharged over the plate 24 to any suitable 40 conveyor or receptacle.

I claim as my invention:

1. A concentrator comprising: an inclined flexible screen; a plurality of hollow riffles spaced lengthwise of said screen and extending therethrough; means whereby air under pressure may be forced upwardly through said screen; and means whereby said screen may be subjected to the downward action of a vacuum. 50

2. A concentrator comprising: an inclined flexible screen; a plurality of hollow riffles spaced lengthwise of said screen and extending therethrough; retarding means in each of said riffles; means whereby air under pressure may be forced upwardly through said screen; and means whereby said screen may be subjected to the downward action of a vacuum. 55

3. A concentrator including: an inclined flexible screen; a plurality of hollow riffles spaced lengthwise of said screen and extending therethrough; an air duct communicating with the under side of said screen; a vacuum duct communicating with the under side of said screen; a valve controlling said air duct; a valve controlling said vacuum duct; and means for alternately opening and closing said valves. 60

In testimony whereof, I have hereunto set 70 my hand at Tonopah, Nevada, this 9th day of May, 1921.

FRANK E. HAWKESWORTH.
